S. F. TRIPPLETT

GRAPE STEMMING DEVICE

Filed May 5, 1924

INVENTOR

Stanley F. Triplett

BY George J. Webster

ATTORNEY

UNITED STATES PATENT OFFICE.

STANLEY F. TRIPPLETT, OF CERES, CALIFORNIA.

GRAPE-STEMMING DEVICE.

Application filed May 5, 1924. Serial No. 711,104.

To all whom it may concern:

Be it known that I, STANLEY F. TRIPPLETT, a citizen of the United States, residing at Ceres, county of Stanislaus, State of California, have invented certain new and useful Improvements in Grape-Stemming Devices; and I do declare the following to be a full, clear, and exact description of the same, reference being had to the accompanying drawings, and to the characters of reference marked thereon, which form a part of this application.

This invention relates to a device for removing the stems from grapes, my main object being to provide a machine for the purpose which will automatically remove the stems from individual grapes, without any manual assistance and without the danger of the grapes being bruised, split or crushed in the operation.

My apparatus is particularly designed to be used in stemming Thompson seedless grapes, which, while easily broken apart from a bunch, still have short stems attached thereto. The lack of a machine for removing the stems, and the impossibility of doing so quickly and cheaply by hand, has heretofore retarded the canning of these and similar grapes on a commercial basis. With the use of my apparatus, this difficulty is overcome, and the grapes may be quickly and easily prepared for canning.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views.

Fig. 1 is a top plan view of the apparatus. Fig. 2 is a cross section, enlarged, on the line 2--2 of Fig. 1.

Fig. 3 is a longitudinal section of the device.

Referring now more particularly to the characters of reference on the drawings, the numeral 1 denotes a smooth-faced member, preferably of sheet iron or the like, which is formed with a plurality of transversely spaced troughs 2, extending from end to end of the member 1.

The member 1, and consequently the troughs, while in a common horizontal plane transversely, have a slope from end to end, the angle of this slope being sufficient to cause any grapes placed in the troughs, to roll along the same by gravity.

The troughs are slotted along their bottoms as at 3, the slots having a width about half that of the troughs, and being bridged across at suitable intervals as at 4 to prevent undue weakening of the sheet of metal of which the troughs are formed.

Under the troughs are soft-rubber rollers 5, extending the full length of the device and journaled at their ends as at 5a. These rollers are arranged in contacting pairs whose line of contact lies in a vertical plane centrally of the slots 3. The rollers are geared or otherwise connected together to be driven in common in such a manner that the rollers of each pair will move toward each other and downwardly from their upper faces.

Extending lengthwise of and adjacent the opposite sides of the rollers forming the so pairs are wires 6, for the purpose herein-after set forth.

In order to prevent any tendency of the rollers, which are unsupported between their ends, from spreading transversely when any stems pass therebetween, additional and non-resilient rollers 7 are mounted to engage the outermost of the transversely alined pairs of the rollers 5, as shown in Fig. 2.

An apron 8 leads to the upper ends of all the troughs, and above the apron and beyond the troughs I preferably mount a fixed grading screen 9. Above this screen are spaced shaking screens 10 of suitable character, flexibly mounted in any well known manner and arranged to be agitated by any of the suitable mechanisms commonly used for the purpose.

In operation, the grapes to be stemmed are placed, in the form of bunches, on the uppermost shaker screen. The shaking action to which the grapes are subjected while on these screens will cause most of the grapes to be separated from the main or bunch stem, and they will drop through the shaker and grade screens onto the apron 8, from which they will roll into the troughs, whose width is such as to accommodate one grape of an average size, as indicated at 11. In rolling down the troughs, the tendency is

for the stems of the grapes to project through the slots at some point in the length thereof, when they will be at once engaged and pulled off by the oppositely turning and 5 yieldable rollers thereunder.

The rollers are of small diameter, so that their point of contact will be but a short distance below the troughs, thereby insuring that short stems will be caught and removed.

10 The stems when thus removed, will pass between and below the rollers, and in the event that they should stick to the rollers and tend to pass up and around the same, the wires 6 will act as wipers and prevent 15 the stems from so doing, causing the latter to drop from the rollers.

Should any stems be missed with the initial passage of the grapes along the troughs, it is an easy matter to dump them onto the apron to undergo another stemming operation.

The rollers may be driven in any suitable manner depending somewhat on the size of the machine.

25 I have indicated one of the rollers 5 as having a pinion 12, meshed with a gear 13 whose shaft 14 may be connected to a power or hand drive of suitable character.

While I have shown three troughs and a 30 corresponding number of stemming rollers, as many of said troughs as may be necessary may of course be employed in a single machine.

The apron 8 preferably has a greater slope 35 than the troughs, so that the sides of the intervening ridges 1^a formed in the member 1 between the troughs will automatically converge and merge with the apron thereby forming means to guide the grapes from the

40 apron into the troughs.

While I have specifically described this structure as being intended for grape-stemming, it will be evident that it may be used 45 for stemming other fruit, with possibly some modifications in construction and arrangement to suit different fruits.

The sides of the troughs are nearly 50 straight from their upper ends to the rollers, whose contour said sides then follow to the slots. This enables the grapes to seat close to the rollers while not actually contacting with the same and the rollers being of small diameter, will engage short stems. The width between the trough sides is less than

55 the length of the grapes, which are oblong in shape. The grapes are thus caused to

roll along the troughs with their major axes in a vertical plane.

From the foregoing description it will be readily seen that I have produced such a 60 device as substantially fulfills the objects of the invention as set forth herein.

While this specification sets forth in detail the present and preferred construction of the device, still in practice such deviations from such detail may be restored to as do not form a departure from the spirit of the invention, as defined by the appended claims.

Having thus described my invention, what 70 I claim as new and useful, and desire to secure by Letters Patent is:

1. A fruit stemming device including a trough down which the fruit is adapted to roll single file, said trough having a slot 75 along its bottom, driven rollers under the trough and arranged to engage and pull off any stems projecting through the slot, and wires adjacent and extending lengthwise of the rollers beyond the line of contact thereof in the direction of their rotation for wiping off any stems sticking to the rollers.

2. A grape stemming device including a pair of parallel and adjacent rollers adapted 85 to be rotated so that their upper faces turn toward each other, and a trough above the rollers and disposed centrally therebetween; the bottom of the trough being slotted and depending below the level of the upper edges 90 of the rollers and following the peripheral contour of such rollers to the edges of the slot whereby to support a grape in close proximity to the rollers so that a short stem will be gripped therebetween.

3. A grape stemming device including a pair of parallel and adjacent rollers adapted 100 to be rotated so that their upper faces turn toward each other, and a trough above the rollers and disposed centrally therebetween; the bottom of the trough being slotted and depending below the level of the upper edge of the rollers and the sides of the trough being substantially vertical and spaced apart a distance slightly greater than the diameter of a grape, whereby the latter will tend to assume a position in the trough with its stem projecting through the slot.

In testimony whereof I affix my signature.

STANLEY F. TRIPLETT.
